SPARK PLUGS

George D. Suter, Wauwatosa, Wis., assignor to Globe-Union Inc., Milwaukee, Wis., a corporation of Delaware

Filed July 7, 1959, Ser. No. 825,554

2 Claims. (Cl. 313—131)

This invention relates to surface discharge spark plugs for low voltages wherein a separating body is arranged between the electrodes and the spark is formed over the free active surface of such body.

In plugs of this type the outer electrode is generally of cylindrical shape (often forming the outer shell of the plug) and the inner electrode, although of various shapes, is positioned so that its parts are uniformly spaced from the sparking end of the cylindrical outer electrode. When voltage is applied to the electrodes ionization and arc breakdown will occur across the surface of the separating body between the electrodes at any one of many different locations around the cylindrical outer electrode. During continued operation of the plug the arc will tend to move angularly around the sparking end of the cylindrical outer electrode.

This moving arc phenomenon is not objectionable in many installations and may be desirable in some since it tends to spread electrode erosion uniformly over the sparking faces of the electrodes. However, in some installations it is important the spark take place at a specific location inside a cylinder of an internal combustion engine, for example, to thereby improve operating efficiency.

It is the object of this invention to provide a spark plug of the type described wherein the spark will always occur along the same path over the separating body between the electrodes.

This object is attained by a spark plug having a hollow tubular first electrode with an insulating or semi-conductive separating body disposed within such first electrode. A second electrode is embedded in the separating body spaced from the first electrode. To fix the location of the spark, I provide an electrode extension connected to one of the electrodes and extending towards the other. Such electrode extension is embedded in the separating body and terminates at a point spaced a short distance from the other electrode so that when voltage is applied to the electrodes a concentrated field is produced at the end of the electrode extension. This causes ionization and arc breakdown across a surface of the separating body between the end of the electrode extension and the electrode spaced from it. Thus, by properly positioning the spark plug in a cylinder of an internal combustion engine, for example, it is possible to locate the spark and maintain it at any desired location within the cylinder.

Other objects and advantages will be pointed out in, or be apparent from the specification and claims, as will obvious modifications of the one embodiment shown in the drawings, in which:

Figs. 1 and 2 are a side elevation view (with parts broken away) and a bottom plan view, respectively, of a spark plug embodying my invention.

The particular application of this invention shown in the drawings is incorporated in a spark plug of standard design, except for novel differences set forth hereinafter.

A steel center terminal or stud 10 is sealed in place

2

in a high alumina porcelain core 12. A nickel alloy connector 14 is connected to the terminal 10 and extends beyond the inner end of core 12, as shown. The inner end of the connector is slotted to provide a forked end 16 which makes contact with an electrode assembly 18. Core 12 is held within a steel shell 20 against a gasket 22. The threaded end of shell 20 has a bore with an inwardly facing shoulder 24 formed at the inner end. The electrode assembly 18 is mounted in the bore 10 against shoulder 24 with forked end 16 of connector 14 connected to such assembly.

The principal feature of this invention resides in the electrode assembly comprising an outer sleeve-like ground electrode 26 and a center electrode 28 embedded in or in firm contact with a separating body 30 of insulating or semi-conductive material. Center electrode 28 has an axially extending body portion 32 with an enlarged head 33 drilled to have a press fit on forked end 16 of connector 14. To positively locate the arc, with respect to the terminals, I provide a radially extending portion 34 on center electrode 28 which terminates just short of outer electrode 26 (Fig. 2).

Thus, when voltage is applied at the terminals a concentrated electric field is produced at the end of electrode portion 34 causing ionization and arc breakdown across surface area 36 of separating body 30, as clearly shown in Fig. 2. All sparking occurs across area 36 between the exposed surface at the end of portion 34 and the exposed end surface of electrode 26 lying the shortest distance away from the end of portion 34. This results because the density of an electric field is inversely proportional to the square of the distance between the electrodes. Thus, it is seen that by properly positioning a spark plug embodying my invention in a cylinder of an internal combustion engine, for example, it is possible to have the spark always occur at a desired location inside the cylinder.

One way to make the electrode assembly described above is to first position the electrodes properly in a jig which is capable of withstanding high temperatures without distorting. The insulation material 30 is then introduced as a fine powder into the areas between the electrodes and the assembly is heated to the softening point of the insulating material and the softened material compacted around the electrodes. The firing end of the assembly is finally prepared (after cooling) by grinding or machining to expose the electrodes surfaces and provide the desired surface gap over the insulating material.

Although but one embodiment of the present invention has been illustrated and described, it will be apparent to those skilled in the art that various changes and modifications may be made therein without departing from the spirit of the invention or from the scope of the appended claims.

I claim:

1. In a low tension surface discharge spark plug, a hollow tubular first electrode, a separating body disposed within and in contact with said first electrode and forming a sparking surface flush with the outer end of said first electrode, a second rod-like electrode embedded in said separating body concentric with and spaced from said first electrode and having a surface flush with the sparking surface of said separating body, and an electrode extension connected to one of said electrodes and extending towards the other electrode, said electrode extension embedded in said separating body and having a surface substantially flush with the sparking surface of said separating body, said electrode extension terminating at a point more closely spaced from said other electrode than any other parts of said electrodes so that when voltage is

applied to said electrodes a concentrated field is produced at the end of said electrode extension causing ionization and arc breakdown across a surface of said separating body between the end of said electrode extension and said other electrode.

2. In a low tension surface discharge spark plug, a cylindrical body of insulating material having a surface over which sparking may occur, electrodes in engagement with and embedded in said body to provide spaced exposed surfaces flush with said surface of said body, at least one of said electrodes having a portion of its exposed surface projecting therefrom and flush with said surface of said body so as to be more closely spaced

than the remainder of said exposed surfaces to define a small area of said body surface over which all effective sparking occurs.
